CORRECTING SPRING ALIGNING
SPACER RING

Brenner B. Fox, San Antonio, Tex.

Application August 21, 1951, Serial No. 242,860

2 Claims. (Cl. 267—60)

1

The invention relates to correcting spring aligner spacer rings for automobiles, and other similar vehicles, machines, and the like.

One important object of this invention is the production of a simple and efficient spacer of material thickness which is adapted to fit into engagement with the end of a supporting coil spring for the purpose of returning a supported vehicle body to a selected height or to its original height, after the supporting spring has become sagged through use.

A further object of this invention is the production of a correcting spring aligning spacer ring which is adapted to extend into and about the end of a vehicle body supporting coil spring, and is of a selected thickness, to return a supported body to a correct height and compensate for the sag in the spring which has occurred through use and to thereby bring the supported body back to its proper original alignment.

Other objects and advantages of the present invention will appear throughout the following specification and claims.

In the drawing:

Figure 1 is a top plan view of the spacer ring; Figure 2 is a bottom plan view thereof;

Figure 3 is a side elevational view;

Figure 4 is an enlarged fragmentary transverse sectional view;

Figure 5 is an enlarged fragmentary transverse sectional view showing a series of rings in stacked relation.

By referring to the drawing, it will be seen that 10 designates the rigid ring-like body formed of metal which is of substantial selected thickness to compensate for the usual or anticipated sag of a body supporting spring of a selected type. The body 10 is provided with a deep circumferential channel or inset groove 11 in its upper face defining an outer ring 12 and an inner rim 13. A plurality of radiating reinforcing ribs 14 extend transversely and vertically between the rims 12 and 13 and are located within the channel or groove 11. Each rib 14 is provided with a central vertical post 15 which preferably is circular in cross-section for decorative as well as for reinforcing reasons. These ribs 14 are spaced circumferentially within the channel 11, as shown in Figure 1. The structure above described provides a body of substantial thickness, which is light in weight and at the same time is reinforced by the ribs 14 and post 15 to adequately support the desired weight and to withstand the shock to which it may be subjected.

As will be noted particularly in Figure 4, the

2

body 10 is provided with a flat under face 16 and an inwardly and downwardly inclined flange 17 is carried by the inner periphery of the ring-like body 10. The outer face 18 of the flange 17 is inclined at a properly selected angle to return the end convolution 19 of the supporting spring 20 to its normal or proper circumference when the ring-like body 10 is placed upon the end of the spring 20 in a manner whereby the bottom face 16 of the body 10 engages the top face of the convolution 19 and the inclined face 18 engages the inner face of the convolution 19. In Figure 4 the original normal position of the convolution 19 is shown in dotted lines, and the sagged position of the convolution 19 is shown in full lines. It will be noted by considering Figure 4, that the original diameter of the upper convolution 19 shown in dotted lines is in vertical alignment with the corrected full line position. The upper convolution 19 is shown in full lines returned to its proper and corrected circumference by means of the inclined face 18 of the flange 17. The ring-like body 10 will therefore hold the end of the spring under a tension in tightly gripping contact with the under face 16 of the body 10 and the inclined face 18 of the flange 17. This will prevent rattle and will eliminate unnecessary noise which otherwise would be present. The size of the ring, its thickness, and the angle of the flange may be varied to suit the size, type and make of the supported body and springs which are to be corrected in order to compensate for the sag which normally may be expected in a coil spring before it settles to a normal height. The inclined flange 17 will facilitate the fitting of the body 10 in engagement with the end of the spring 20. As the flange 17 is inserted into the upper convolution 19 and weight is placed upon the body 10, the inclined face 18 will cause the convolution 19 to expand to its proper diameter where the convolution 19 will engage the flange 17 under a tension and will also contact the under face 16 of the body 10.

The spacer ring preferably fits upon the top of the spring 20 although if it is desired it may be used in an inverted position upon the bottom of the spring. It is preferable to use the ring upon the top of the spring. The conventional guide plate 21 may rest upon the body 10, as shown in Figure 4, and the lugs or guide fingers such as the guide finger 22, shown in Figure 4, will abut the inner inclined face 23 of the flange 17 thereby anchoring guide plate 21 and ring body 10 against shifting. The outer face of the finger 22, as shown in Figure 4, contacts the inner face of

the convolution 19 when the ring body 10 is not in position and the point of contact of the convolution 19 with the face 18 of the flange 17 is in vertical alignment with the outer face of the lug 22 as shown in Figure 4 for the purpose as previously pointed out.

As shown in Figure 5, the angle of the flange 17 of each ring-like body 10 will facilitate the stacking of the rings one upon the other so that the bottom face 16 of the body 10 will fit flat upon the top edges of the ribs 13 and 14. The flange 17 of the upper ring will then fit within the next below ring, the rings fitting in nested relation to facilitate packing, storage and shipping.

It should be noted that the spacer will rigidly hold the end of a coil spring against rattle or sound and will also provide a great saving in critical material in the construction of the spacer ring, as well as in the unnecessary replacement of springs. It is a well known fact that springs sag to a calculated or stabilized point during wear or use, and by raising the body contact point, the car upon which the spring is mounted will ride more evenly than would otherwise be the case. It is well known that springs become settled after use and when they reach a stabilized height, the addition of a spacer ring of a selected thickness will return the supported body to its normal height which will then remain substantially constant. Also it is known that the alignment of the front end of a car changes when the springs sag, and therefore the angles of the front end suspension parts are brought back to proper alignment when a spacer of a selected thickness is placed between the spring and the car frame or the lower control arm thereof.

It should be understood that certain detail

changes of construction and design may be employed without departing from the spirit of the invention, so long as these changes fall within the scope of the appended claims.

Having described the invention, what I claim as new is:

1. A correcting spring aligning spacer ring comprising a rigid ring-like body having a deep annular channel formed in one face thereof, radiating ribs extending transversely of the channel and for the depth of the channel to reinforce the ring, and an inclined flange extending at an angle to the body around the inner periphery of the ring.
- 10 2. A correcting spring aligning spacer ring comprising a rigid ring-like body having a deep annular channel formed in one face thereof, radiating ribs extending transversely of the channel and for the depth of the channel to reinforce the ring, an inclined flange extending at an angle to the body around the inner periphery of the ring, and said ribs having circular reinforcing posts substantially centrally of the channel.
